DESIGN FOR A STAPLER MACHINE

Henry Ruskin, Chicago, Ill.

Application September 12, 1945, Serial No. 122,029

Term of patent 14 years

(Cl. D74—1)

To all whom it may concern:

Be it known that I, Henry Ruskin, a citizen of the United States and a resident of Chicago, in the county of Cook and State of Illinois, have invented a new, original, and ornamental Design for a Stapler Machine, of which the following is a specification, reference being had to the accompanying drawing, forming a part thereof, and in which:

Fig. 1 is a top plan view of a stapler machine showing my new design;

Fig. 2 is a perspective view of the same;
Fig. 3 is a side elevational view of the same;
Fig. 4 is a rear elevational view of the same;
Fig. 5 is a front elevational view of the same.

I claim:

The ornamental design for a stapler machine, as shown.

HENRY RUSKIN.
